ROCKING-WALKING TOY

John W. Peltier, San Bernardino, Calif.

Filed June 10, 1959, Ser. No. 819,464

1 Claim. (Cl. 280—1)

The present invention generally relates to a toy or amusement device primarily adapted for use by children but which is not limited to such use since the device may also be used as an exerciser having certain therapeutic values for exercising various muscles such as the muscles of the hands, arms and legs.

The primary object of the present invention is to provide an amusement device or toy generally in the form of a walker which moves forwardly in a step-by-step manner due to the actions of the occupant or operator with there being required certain coordination of movements to effectively propel the device thereby developing coordination of the person employing the device as well as providing an exercising device and a highly interesting and entertaining toy or amusement device.

Another object of the present invention is to provide a toy or exercising device which is extremely simple in construction, easy to use, utilitarian for many purposes and generally inexpensive to manufacture.

These together with other objects and advantages which will become subsequently apparent reside in the details of construction and operation as more fully hereinafter described and claimed, reference being had to the accompanying drawings forming a part hereof, wherein like numerals refer to like parts throughout, and in which:

FIGURE 1 is a perspective view of the toy of the present invention;

FIGURE 2 is a vertical sectional view taken substantially along the center line of the device illustrating the structural details of the riding platform and the other components of the invention;

FIGURE 3 is a schematic side elevation showing an initial position of the components of the toy;

FIGURE 4 is a schematic side elevation showing a progressive position of the components;

FIGURE 5 is a schematic side elevation showing a further orientation of the components; and

FIGURE 6 is a schematic side elevation showing the final position of the components as they again approach the position of FIGURE 3.

Referring now specifically to the drawings, the numeral 10 generally designates the amusement device of the present invention which may be said to include two separate rockable components generally designated by numerals 12 and 14.

The rockable component 12 includes a pair of spaced parallel legs 16 having an enlarged lower end 18 provided with an arcuate lower surface 20 for rockingly engaging a supporting surface. The forward edges of the enlarged lower ends 18 are rigidly interconnected by a transverse rod 22 thus maintaining the legs 16 in properly spaced relation. The upper ends of the legs 16 are each provided with an upwardly extending handle 24 which is inclined forwardly or away from the rockable component 14. The upper ends of the legs 16 are also rigidly interconnected by a transverse rod 26 which extends between the upper end of the leg 16 adjacent the point of attachment of the handles 24.

The rockable component 14 includes a pair of laterally spaced parallel legs 28 having forwardly curved upper ends 30 and enlarged lower ends 32 which have a rearward extension 34 extending behind the rear surface of the leg 28 and receiving a platform 36 therebetween. The platform 36 is provided with downturned end flanges 38 for attachment to the enlarged head 32 and the rear-

2

wardly extending portion 34 by fasteners 40. The forward edge portion of the enlarged head 32 is arcuately curved as indicated by numeral 42 for rockingly engaging a supporting surface with the lower edge of the rearward extension 34 generally being tangential to the lowermost portion of the curved edge 42. The forwardmost ends of the forwardly curved upper ends 30 are mounted on the transverse shaft 26 and the transverse shaft 26 together with the platform 36 serve to retain the legs 28 in rigidly spaced relation. It is pointed out that the legs 28 are disposed inwardly of the legs 16 and will move partially between the enlarged heads 18 during relative pivotal movement of the rockable components 12 and 14 which may also be termed rocker arms.

When using the device of the present invention, the occupant stands upon the platform 36 and will grasp the handles 24. Assuming that the orientation shown in FIGURE 3 is a starting position, the operator standing on the platform 36 would lean forwardly and push on the handle 24 which would cause the leg members 16 to roll or rock on the supporting surfaces. As the device rocks about the curved edge 20 of the leg member 16, the transverse rock 26 will move in an arc generally about the bottom edge 20 of the enlarged head 18 and will also normally swing to seat its own center of gravity which will elevate the enlarged head 32 slightly off the ground and will also permit the legs 28 to swing forwardly as illustrated in FIGURE 4. After the legs 28 are as far forwardly as possible or as is desired, the operator shifts his weight rearwardly and pulls on the handles 24. As soon as all the weight is taken on the rearward extensions 34 of the enlarged elements 32, the legs 16 will be pivoted forwardly thus swinging the enlarged head 18 forwardly due to rearward pressure being exerted against the handles 24. The forward movement of the enlarged lower end 18 is illustrated in FIGURE 6 and will come to rest in substantially the same condition as shown in FIGURE 3. Thus, by alternately leaning forward and pushing forwardly on the handles 24 and then allowing the trailing rocker arm to move upwardly and then rocking backwardly allowing the trailing rocker arm to support the device and thus enables forward movement of the legs 16 due to rearward force being exerted on the handles thereby providing an easily operated step-by-step device which is highly amusing, entertaining and also provides an exercise and develops coordination.

The device may be constructed of any suitable material such as plywood, regular wood, metal or plastic and may be decorated in any suitable manner.

The foregoing is considered as illustrative only of the principles of the invention. Further, since numerous modifications and changes will readily occur to those skilled in the art, it is not desired to limit the invention to the exact construction and operation shown and described, and accordingly all suitable modifications and equivalents may be resorted to, falling within the scope of the invention as claimed.

60 What is claimed as new is as follows:

A combination exercising and amusement device comprising a first pair of parallel members in the form of legs which have a forwardly curved upper end portion, a transverse platform rigidly interconnecting the first pair of members adjacent the lower end thereof and providing a support upon which a person employing the device may stand, a second pair of members disposed in parallel relation exteriorly of the first pair of members, a pivot rod rigidly interconnecting the upper ends of the pair of members and extending through the upper ends of the first pair of members thus pivotally connecting the pairs of members together, said second pair of members being

straight and provided with a rounded bottom surface for rocking engagement with a supporting surface, said first pair of members having a lower edge surface for engagement with a supporting surface, the length of said second pair of members being such that the first pair of members will be elevated off of the supporting surface and swing towards the second pair of members when the second pair of members are disposed in vertical position, each of said second pair of members having a rigid handle extending upwardly from the upper end thereof for providing handles for the person standing on the platform for use when employing the device, said platform and handles being orientated vertically from each other so that a person standing on the platform will have the handles and transverse rod generally disposed in the waist region whereby forward and rearward shifting of weight will propel the device in a step-by-step manner when the

handles are pulled rearwardly thus moving the lower ends of the first pair of members forwardly when the person is leaning rearwardly and the lower ends of the second pair of members is supporting all of the weight, the forward shifting of the weight moving the second pair of members to a vertical position whereby the lower ends of the first pair of members will be elevated from the supporting surface and move by gravity about the rod towards the vertical members.
